UNITED STATES PATENT OFFICE.

JAKOB TOBLER, JR., OF VONWIL, NEAR ST. GALLEN, SWITZERLAND.

EMBROIDERING-MACHINE.

1,258,274.

Specification of Letters Patent.

Patented Mar. 5, 1918.

Application filed July 3, 1916. Serial No. 107,384.

To all whom it may concern:

Be it known that I, JAKOB TOBLER, Junior, a citizen of the Swiss Confederation, and residing at Vonwil, near St. Gallen, Switzerland, have invented certain new and useful Improvements in Embroidering-Machines, of which the following is a specification.

The present invention has reference to certain new and useful improvements in embroidery machines, and relates more specifically to improvements in the cutting mechanism for certain such machines, and the invention essentially resides in the improved construction of cutting device, which includes two divergently disposed cutting members, as will hereinafter be fully described.

I am well aware that there are already known various constructions of cutting devices for severing the embroidered portion along its worked edge from the waste portion of the ground fabric, in which the fabric is fed in between two cutting members. In all of these constructions, as far as I am aware, the two cutting blades are more or less widely interspaced, leaving between them an adjustable slit of even width throughout for the passage of the fabric. Such cutters, however, have been found to operate more or less unsatisfactorily in the case of delicate, fine ground fabrics and also in the case of coarser ground fabrics with intricate edge designs which offer certain difficulties in cutting.

According to the present invention I have succeeded in constructing a cutting device which will readily dispose of the finest or coarsest work with the most intricate edgings, by disposing the two cutting blades at a slight angle relative to one another, which leaves between them a work feed passage of decreasing width, which in operation obviates all objections attaching to the old even-width work intake passage.

The nature of my invention will best be understood, when described with reference to the accompanying drawings, in which Figure 1 represents a plan view of a preferred form of construction of the improved cutting device; Fig. 2 shows an end view, and Fig. 3 a front view thereof. Figs. 4 and 5 respectively show front and plan views of a modified form of construction, and Figs. 6 and 7 vertical sections thereof, through lines A—B, and C—D, of Fig. 4.

In the cutting device according to Figs.

1—3 the blade carrier 1 on its upper face is depressed and in this depression supports the cutting blade 2. A cover plate 3, overlapping this blade, is provided at the ends 60 with laterally extending pins 4 and is journaled therewith in the thickened end portions of the carrier member, flanking the intermediate depressed portion. For operatively pressing the cover plate 3 against the 65 blade, and the latter against the carrier, the leaf spring 5 is provided which is suitably secured at the one end of the carrier, for instance by means of the screws 5', and which contactingly extends the greater extent of the cover plate. To the carrier 1 is hinged by the links 6 a rod 7, from which rigidly depends the elbow member 8 to the front end of which is secured the counter 75 cutter member 9, which is here shown in the form of an angle bar having a beveled upper cutting edge 9'; and the main blade and the counter cutting member are yieldingly interconnected by means of springs 10 and 11, which are operatively interposed 80 between the blade carrier 1 and the rod 7. Of these the spring 10 is a draw-spring and the spring 11 a compression-spring, and the latter is controlled by an adjusting screw 12. The arrangement of these springs and their 85 operative force is so adjusted that the counter cutting member 9 is pressed against the blade always with the required, varying pressure, and the two cutting blades are relatively so disposed that their actual cutting edges contact only to a restricted extent and then diverge from one another, as shown in Fig. 3.

By means of the studs 13 and 14 the cutting device is secured to the embroidering 95 machine, intermediate the two parallel belts which serve to feed the goods to be cut; which parts, being well known in the art and not forming part of my invention, need no illustration and description here.

The cutting device is to be arranged obliquely between the two feeding belts, and thereby also obliquely to the direction of feed of the embroidered goods, as shown in Fig. 1, the stud 13 serving as pivot when 105 changing the angle of adjustment.

In cutting the workpiece *a* (Figs. 1 and 2) it is introduced by hand between the two cutting members 2 and 9 and, by the embroidered edge portion of the fabric catching on the cutting blade 2, is then sharply cut off from the rest of the ground fabric,

following the direction of the cutting device as shown in dotted outline in Fig. 1. By reason of the cutting blade contacting over part of its length with the counter member 9, the fabric on being fed in between the two cutting members is severed already by the mere feed movement, whereby all kinds of embroideries, even the finest qualities, are cut out with the greatest precision; and owing to the yielding connection of blade and counter blade the cutting device readily adapts itself to fabrics of varying thickness.

In the modification illustrated in Figs. 4-7, 1' denotes the blade carrier, 2' the blade, and 13', 14' the studs by which the cutting device is secured to the embroidering machine proper. The blade carrier 1' is provided with a longitudinally extending cross slot 15 (Fig. 7) for the passage of the waste portion of the fabric, cut off from the embroidered portion *a*. To the blade carrier is linked by means of the hinges 16 a cover plate 3' for the blade 2', which latter is secured to the carrier 1' by means of the screws 17. The counter member in this construction is in the form of a second knife blade 9'', which is clamped between a cover plate 18 and an angular support 19, screws 21 holding the several parts together. The support 19 is linked to the blade carrier 1' by means of the hinges 20, which, as shown, are three-part and also connect the cover plate 18 to the support 19. To the blade carrier 1' are further secured three pressure springs 22, bearing against the angular support 19, which latter can be adjusted relative to the carrier 1', against the action of these springs 22, by means of the adjusting screw 23.

As shown in Fig. 4, the blades 2' and 9'' are likewise divergently arranged, whereby an intake slit of decreasing width is present-

ed between the two blades, which slit can be adjusted as to size by manipulation of the screw 23 to accommodate fabrics of varying thickness.

What I claim is:—

1. In a cutting device for embroidering machines, in combination, an upper cutting member, a lower cutting member, means for yieldably connecting the two said cutting members, means for limiting the space between said members, said members being disposed at an angle toward one another whereby a work intake slit of decreasing width is presented between them, means for adjusting the initial width of said slit, and means for operatively connecting said cutting device to the embroidering machine frame.

2. In a cutting device for embroidering machines, in combination, an upper cutting member, comprising a blade carrier, a blade, a cover for said blade, and means for operatively securing said parts to one another; a lower cutting member, comprising a blade carrier, a blade, a cover for said blade, and means for operatively securing said parts to one another; hinge connections between the said two cutting members; resilient means interposed between the said two cutting members, and means for regulating the action of such resilient means, the said two cutting members being disposed at an angle toward one another in such manner that between them a work intake slit of decreasing width is presented, and means for operatively connecting said cutting device to the embroidering machine proper.

In testimony whereof I affix my signature in presence of two witnesses.

JAKOB TOBLER, JUN.
